UNITED STATES PATENT OFFICE

2,296,245

FILING ELEMENT

Raymond C. Finch, Jamestown, N. Y., assignor to
 Art Metal Construction Company, Jamestown,
 N. Y., a corporation of Massachusetts

Application December 12, 1941, Serial No. 422,692

4 Claims. (Cl. 129—16.7)

This invention relates to card files and is more particularly concerned with a novel index and signal arrangement in which an indicator slide or signal is associated with a support such as a card or similar element and a transparent sheath attached to the card as by clasping the latter and also by interlocking therewith. The invention will best be understood by reference to the following description when taken in connection with the accompanying drawing of one specific embodiment thereof, while its scope will be pointed out more particularly in the appended claims.

In the drawing:

Fig. 1 is a front elevation of an index or file card and indicator arrangement embodying the invention;

Fig. 2 is a front elevation of a portion of Fig. 1 on an enlarged scale with parts broken away and in vertical section, the better to illustrate the invention; and

Fig. 3 is a sectional view on an enlarged scale on line 3—3 of Fig. 2.

Referring to the drawing and to the embodiment of the invention illustrated therein by way of example, there is shown a card index arrangement comprising a support such as a sheet of paper 4 having at the top a fold 6 perforated to receive a wire hanger not shown, the lower, marginal portion of the sheet being clasped by a transparent sheath 8 (see Fig. 3) which in this instance is further secured to the sheet 4 as by an interlocking arrangement now to be described. To this end, the sheet 4 is folded at 10 to provide a rebent or upturned flange 12, while the sheath is folded at 14 to provide a rear wall 16 and a front wall 18, the latter in turn being folded at 22 and turned downwardly to provide a flange 24, thus producing a channel 26 which receives the upturned flange 12 of the sheet 4.

The upturned flange 12 is provided with one or more, herein a horizontal series of spots, symbols, or characters 28 for cooperation with a preferably transparent indicator slide 30 folded at 32 to provide an upturned flange 34 which lies between the upturned flange 12 of the sheet 4 and the front wall 18 of the sheath 8. The slide 30 has a handle portion 36 at the rear of the sheet 4 and extending upwardly from the upper edge of the rear wall 16 of the sheath 8 to be grasped to enable the indicator slide to be shifted horizontally to cause its upturned flange 34 to register with successive symbols or characters 28. The indicator slide is introduced endwise into the sheath about the fold 10 of the sheet 4 and by grasping the handle 36 at the rear of the sheet may be moved horizontally to indicate a desired condition which may be representative of percentages, dollars, locations, and other desired information. The symbols or char-

acters, of course, are visible through the front flange 34 of the slide in the case of a slide which is transparent.

Having thus described one embodiment of the invention, what I claim and desire by Letters Patent to secure is:

1. The combination of a transparent sheath folded to provide a rear wall and a front wall, the latter in turn being folded downwardly to provide a flange and a channel between said flange and said front wall, a sheet having an upturned flange received in said channel and bearing one or more symbols or characters visible through said front wall, and an indicator slide folded to provide an upturned flange disposed behind said front wall and in front of the upturned flange of said sheet in position to cooperate with said symbols or characters, said indicator having a handle portion at the rear of said sheet and at the front of said rear wall and extending upwardly from the upper edge of said rear wall of said sheath where it may be grasped to shift said slide horizontally.

2. The combination of a sheet having a horizontal series of symbols or characters on its front face, an indicator slide folded to provide a front flange for cooperation with said symbols or characters and having a handle portion at the rear of said sheet, and a transparent sheath having a front wall which overlies said front flange and covers said symbols or characters and a rear wall which overlies a part of said handle portion and a portion of the rear face of said sheet below said handle.

3. The combination of a transparent sheath folded to provide a front wall and a rear wall, a sheet clasped between said walls and bearing on its front face a horizontal series of characters or symbols visible through said front wall, and an indicator slide folded to provide an upturned flange disposed behind said front wall and in front of said sheet in position to cooperate with said symbols or characters, said indicator slide having a handle portion at the rear of said sheet and at the front of said rear wall above the upper edge of said rear wall where it may be grasped to shift said slide horizontally.

4. The combination of an interlocking sheet and transparent sheath, said sheet bearing on its front face a horizontal series of symbols or characters, and said sheath having a front wall overlying said symbols or characters, and an indicator slide having a front portion which overlies the front face of said sheet and underlies said front wall for cooperation with said symbols or characters and having a rear portion which overlies the rear face of said sheet and provides a handle which may be grasped to shift said slide horizontally.

RAYMOND C. FINCH.
